(57) **CLAIM**

I claim the ornamental design for an antenna housing, as shown and described.

DESCRIPTION

FIG. 1 is a top perspective view of a first embodiment of an antenna housing showing my new design;

FIG. 2 is a bottom perspective view thereof;

FIG. 3 is a top plan view thereof;

FIG. 4 is a bottom plan view thereof;

FIG. 5 is a left elevational view thereof;

FIG. 6 is a right elevational view thereof;

FIG. 7 is a front elevational view thereof;

FIG. 8 is a rear elevational view thereof;

FIG. 9 is a top perspective view of a second embodiment of an antenna housing showing my new design;

FIG. 10 is a bottom perspective view thereof;

FIG. 11 is a top plan view thereof;

FIG. 12 is a bottom plan view thereof;

FIG. 13 is a left elevational view thereof;

FIG. 14 is a right elevational view thereof;

FIG. 15 is a front elevational view thereof; and,

FIG. 16 is a rear elevational view thereof.

The broken lines and portions contained within are not claimed. In the second embodiment of the antenna housing formed in accordance with the present invention, as shown in FIGS. 9-16 of the drawings, the stippling represents a gloss surface, the horizontal linear shading represents a brushed surface and the cross-hatching represents a matte surface.
